CLAIM

(57) I claim the ornamental design for a touch monitor, as shown and described.

DESCRIPTION

FIG. 1 is a front perspective view of a touch monitor showing my new design;

FIG. 2 is a front view thereof;

FIG. 3 is a top view thereof;

FIG. 4 is a rear view thereof;

FIG. 5 is a bottom view thereof;

FIG. 6 is a left side view thereof;

FIG. 7 is a right side view thereof; and,

FIG. 8 is rear perspective view thereof.

The broken lines are directed to environment and are for illustrative purposes only. The broken lines form no part of the claimed design.
